CLAIM

The ornamental design for a light projector, as shown and described.

DESCRIPTION

FIG. 1 is a perspective view of a light projector;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.
The portions of the light projector shown in broken lines
form no part of the claimed design.
